UNITED STATES PATENT OFFICE

RAYMOND M. ANDERSON, OF DETROIT, MICHIGAN, ASSIGNOR TO GEORGE M. HOLLEY,
OF DETROIT, MICHIGAN

DOWNDRAFT CARBURETOR

Application filed May 10, 1929. Serial No. 361,942.

This invention refers specifically to means for accelerating the fuel supply when the throttle is opened.

Fig. 1 shows diagrammatically all the essential elements of the carburetor.

Fig. 2 shows a detail elevation of the throttle control.

Fig. 3 is a plan view showing the arrangements of the parts.

10 In Fig. 1, A is the air entrance, B is the throttle valve located in mixture outlet L and operating a ratchet C through a spur wheel C (see Fig. 2) which raises and lowers, by means of the bracket M, the needle valve D which controls the fuel flowing from the float chamber E through a passage F.

The flow through F is also controlled by the float valve K' controlled by the float K. This float is enclosed in a special auxiliary 20 float chamber H, the upper part of which has a vent J controlled by the float valve K' which is formed on the upper end of the float valve K'. The chamber H is also vented at K² to the float chamber E which is vented at 25 E² to the atmosphere. An overflow E is also provided.

The fuel level in E is maintained at XX by the conventional float mechanism G. The fuel nozzle N forms the outlet from the passage F controlled by the needle valve D and is located 1/2" below XX and discharges into the throat Y of the mixing chamber which is of Venturi form. Concentric with N is the passage O so that a small annular passage is 30 formed between N and O. This passage O communicates with the vertical passage P which communicates with the mixture outlet L through the restricted outlet P. The vent J of the smaller auxiliary float chamber H 35 communicates through passages S, S', S² and S³ with the passage P for the purpose to be described later.

The fuel pump shown in Fig. 1 comprises a cylinder U with skirt depending below the level XX in the float chamber and a piston W which slides freely within the cylinder U is provided. The piston W is adapted to be raised by the hook link V attached to the plate M and to descend under its own weight. 45 Connected to the end of the hook valve V

is a valve R which is loosely connected so as to automatically seat itself on the inside of the piston W and close the opening Q provided therethrough. In the fuel outlet T leading out of the upper part of the cylinder U is a check valve Z. The fuel outlet T discharges into the air entrance A.

An air chamber Z' is provided in the upper wall of the float chamber having a restricted communication with the nozzle T for a purpose to be described. The discharge outlet from T is restricted as shown at T'.

The piston W is preferably made of some material such as Invar which has a low coefficient of expansion, lower than that of the cylinder U, which may be made of brass, aluminum or bakelite.

When the engine to which the carburetor is attached is started, a sufficient depression is created in the mixture outlet L to cause the air in the upper part of the auxiliary float chamber H to flow through J and the passages S', S², and S³ to the mixture outlet passage P, P'. The float K' is thereby raised thus opening the valve K' and closing the valve K'. The fuel then flows by gravity from E through F to nozzle N where some of the fuel flows around the nozzle N through the passage O to the passage P and so issues at the point P' into the mixture outlet L. This arrangement insures steady silent idle running.

On opening the throttle the depression at O and also Y increases just as the depression at L and P' decreases so that at all times there is a depression in H sufficient to cause the valve K' to open the fuel outlet. When the throttle is open the rack C and the pinion C' raises the bracket M and thereby raises the needle valve D which regulates the flow of fuel through F to N. On suddenly opening the throttle the hook V raises the piston W so quickly that the fuel in U normally cannot escape by leaking past the piston W and it is therefore ejected into the air entrance A, past the check valve Z through the passage T. The air in Z' is compressed as fuel is drawn through into T faster than it can escape into the mixing chamber. It will be noted that repeated openings of the throt-

tle in quick succession will not cause an excessive amount of fuel to be pumped into the air entrance because the piston W can only return as fast as gravity will permit.

5 Owing to the difference in coefficients of expansion of the materials of which the cylinder U and the piston W are made, the effectiveness of the pump depends upon the temperature. At relatively high temperatures, 10 for example, higher than 70° F., the clearance between the piston W and the cylinder U becomes so great that a considerable portion of the fuel displaced by the piston W leaks back into the float chamber E and 15 the pump thereby becomes less effective. It will be noted that the fuel for acceleration enters into the air entrance above the mixing chamber through which it flows by gravity on to the throttle.

20 What I claim is:

1. In a carburetor having a throttle valve, accelerating means comprising a throttle operated pump, a cylinder made from material having a relatively high coefficient of expansion, a piston made from a metal having a relatively low coefficient expansion, said piston being adapted to be operated by said throttle.

2. In a carburetor having a constant level 30 fuel supply chamber, a fuel nozzle fed therefrom, a mixing chamber, a throttle valve, accelerating means comprising an open ended inverted cylinder having its skirt depending below the level in said supply chamber, a piston 35 slidable therein and having an opening therethrough, a valve engaging with the under side of said piston and adapted to seal said opening, link means connecting said valve with said throttle whereby the piston 40 is raised when the throttle is opened, a fuel outlet from said cylinder, a check valve in said outlet, and a passage from said outlet to said mixing chamber.

3. In a carburetor having an air entrance 45 and a throttle valve, accelerating fuel supply means comprising a cylinder, a piston therein adapted to be operated by said throttle, a fuel entrance to said cylinder controlled by said throttle, a fuel outlet from said cylinder, a 50 check valve in said outlet, a restricted fuel nozzle discharging into said carburetor air entrance, a passage connecting said fuel nozzle and the outlet from said cylinder, a closed air chamber communicating with said passage for the purpose described.

55 In testimony whereof he affixes his signature.

RAYMOND M. ANDERSON.
